UNITED STATES PATENT OFFICE

168,601

CORNER TABLE OR THE LIKE

Everett A. Swanson, Naval Base, S. C.

Application October 26, 1951, Serial No. 17,133

Term of patent 3½ years

(Cl. D33—14)

To all whom it may concern:

Be it known that I, Everett A. Swanson, a citizen of the United States, residing at Naval Base, in the county of Charleston and State of South Carolina, have invented a new, original, and ornamental Design for a Corner Table or the like, of which the following is a specification, reference being had to the accompanying drawing, forming a part thereof.

In the drawing:

Figure 1 is a perspective view of a corner table or the like, showing my new design.

Figure 2 is a horizontal sectional view thereof taken substantially along a plane as indicated by the line 2—2 of Figure 1.

I claim:

The ornamental design for a corner table or the like, substantially as shown.

EVERETT A. SWANSON.
